UNITED STATES PATENT OFFICE.

PAUL C. OSCANYAN, OF BOGOTA, NEW JERSEY, ASSIGNOR TO STAR BALL PLAYER COMPANY, A CORPORATION OF NEW JERSEY.

SCORE OR BULLETIN BOARD.

1,321,940.

Specification of Letters Patent.

Patented Nov. 18, 1919.

Application filed April 28, 1917. Serial No. 165,172.

To all whom it may concern:

Be it known that I, PAUL C. OSCANYAN, a citizen of the United States, and a resident of Bogota, in the county of Bergen and 5 State of New Jersey, have invented certain new and useful Improvements in Score or Bulletin Boards; and I do hereby declare the following to be a full, clear, and exact description of the invention, such as will enable others skilled in the art to which it 10 pertains to make and use the same.

This invention relates to improvements in score or bulletin boards,—one object of the invention being to provide means whereby 15 the runner members shall be capable of movement independently of each other.

A further object is to so construct and arrange the runner members that the same shall be capable of passing each other.

20 A further object is to so construct and arrange the device that the independently movable runners may be stopped at predetermined positions, either at one of the bases or between bases.

25 A further object is to provide simple means at the bases to denote that a player is "out."

A further object is to provide simple and efficient operating mechanism for the runner 30 members.

A further object is to so construct the device that all of the runner members shall be operable by a single mechanism common to them all and still permit movement of any 35 one or more of said runner members independently of the others.

A further object is to provide simple means under the control of the operator for illuminating the ball.

40 With these and other objects in view, the invention consists in certain novel features of construction and combinations of parts as hereinafter set forth and pointed out in the claims.

45 In the accompanying drawings; Figure 1 is a rear view of my improved score board; Fig. 2 is a front view of the same, on a smaller scale; Fig. 3 is an enlarged detail view showing the runner members and operating means therefor; Fig. 4 is a view in section on the line 4—4 of Fig. 3; Fig. 5 is a view showing the details of the mounting for the runner members; Fig. 6 is a transverse section through one of the runner members; 50 Fig. 7 is an enlarged view taken on the line

7—7 of Fig. 1; Fig. 8 is an enlarged sectional view on the line 8—8 of Fig. 1; Fig. 9 is an enlarged sectional view on the line 9—9 of Fig. 1 and Fig. 10 is a view in which the means for lighting the ball are shown diagrammatically.

1 represents suitable framework, upon the central portion of which a board or sheet 2 is secured and is designed to represent a base-ball field. At respective sides of the 60 field 2, racks 3, 3, are attached to the frame 1 and adapted for the reception of inserts bearing the names of the clubs and their players and other identifying and record data.

70 The diamond of the field is formed by providing elongated openings 4 representing the runways between bases, and open frames 5, 6, 7, 8 at the corners of the diamond, representing the several bases.

75 A frame 9 approximating the shape of the diamond is secured to the field sheet 2 and spaced somewhat from the back thereof, said frame 9 being thus located in rear of the runways 4 and the base frames 5, 6, 7 and 80 8 so that runner members (hereinafter described) may be caused to move between the runways and said frame 9. The purpose of the frame 9 is to support a series of adjustable stop pins 10 for stopping the runner 85 members at the bases or at points intermediate thereof and to form a bottom for the base path at the rear of openings 4. Each stop pin may be mounted to move longitudinally in a tubular guide post 11 secured to the frame 9 and provided at its rear end with a ring 12 or other suitable device to facilitate the manual manipulation of the pin to move the same into or out of the path of the runner members. Stop pins are located 90 close to the several bases so that the runner members may be stopped at the bases and other stop pins are provided short distances from the bases so that the runner members may be permitted to overrun the bases. Stop 100 pins may be provided both to the right and left of home base so that either a left or a right hand batter may be held at "home" while a base runner is attempting a "steal" of a base.

105 In the construction of the device shown in the drawing, I may employ four runner members 13 radiating from a shaft 14 projecting rearwardly from the center of the diamond portion of the board. This shaft 110

is provided at one end with a disk 15 secured to the back of the board opposite the pitcher's position and the free end of this shaft is threaded as indicated at 16. A 5 tubular shaft 17 is mounted to turn on the fixed shaft 14 and provided at one end with a disk 18,—said tubular shaft being also provided with a longitudinal keyway 19. The runner members 13 are mounted freely 10 near their inner ends upon the tubular shaft 17 and alternating with said runner members, are metal disks 20 provided with keys 21 to enter the key-way in said tubular shaft,—fiber washers 22 being interposed between the several disks and runner members. 15 A worm wheel 23 is keyed to the outer end of the tubular shaft 17 and spaced from the outer disk 20 by means of a sleeve 24. A bracket 25 is mounted on the fixed shaft 14 adjacent to the worm wheel and a disk 26, 20 connected with said fixed shaft by a key 26^a, bears against said bracket. A winged nut 27 is located on the threaded end of the fixed shaft and bears against the disk 26. 25 Between the disk 15 at the inner end of the fixed shaft 14 and the disk 18 rigid with the inner end of the tubular shaft 17, a spring 28 is located,—said spring operating to cause the several runner members, disks and washers to be clamped together in such manner 30 that when the tubular shaft is turned, the several runner members will move together, but so that movement of one or more of said runner members may be prevented by reason 35 of the adjustment of the stop pins, but the other runner members can move independently of the runner members which may be held by stop pins. Thus it will be seen that the mounting means of the runner members 40 constitute, in effect, friction clutch devices for said members, and the frictional resistance afforded between the parts may be readily regulated by adjusting the tension of the spring 28,—which adjustment may be readily effected by manipulation of the winged 45 nut 27.

The bracket 25 affords bearings 29 for an operating shaft 30 carrying a worm 31 to mesh with the worm wheel 23. This shaft 50 also has a bearing in a bracket 31^a secured to the frame 1 and is provided with a balanced crank handle 32 within convenient reach of the operator.

Each runner member 13 is made extensible 55 so that the same may be lengthened when it is desired that the same shall project past the runway opening, and thus be viewed by the audience, to represent the movement of a player from one base to another, and so that 60 it may engage a stop pin should the latter be adjusted to arrest the movement of the runner member. It will be understood that when a runner member is collapsed, it will not project past the runway openings and 65 hence will be out of sight of the audience.

Each runner member may be made of sheet metal and comprises two parts 33—34 movable one upon the other,—the part 33 having guide wings 35 embracing the part 34, and the latter having a lug 36 at its free end to 70 be engaged by said guide wings for limiting the outward movement of the extensible part 33 of the runner member.

At each of the bases on the board, slides 75 or shields 37 are located and are operable from the back of the board so that they may be moved to close the base frames and thus obscure a runner member which may be behind a base frame.

In the operation of the device, when the 80 shaft 30 is turned by manipulation of the crank 32, motion will be imparted through the worm gearing to the tubular shaft 17 and the tendency will be to move all of the runner members, but such of said runner 85 members as have been extended will be controlled and limited in their forward movement by the disposition of the stop pins. For example; if a runner member is held at second base by a stop pin and a batter reaches first base,—one runner member will remain at "second" and another runner member will be stopped at "first" by the adjustment of the stop pin at the latter base. On the other hand, if the 95 runner member is to move from "second" to "third" on the "play", the stop at "second" will be withdrawn and the top pin at "third" adjusted to arrest the runner member at that base. If an extended runner 100 member be approaching a base frame and it is desired to show that the runner safely reaches the base, the stop pin adjacent to such base will be moved outwardly and the slide or shield 37 at such base will be permitted to remain withdrawn, so that the runner member will be stopped at the base and be visible through the base frame. Should it be desired to indicate that the 105 player is "out" at such base, the operator 110 will move the slide or shield over the base frame and thus obscure the runner member.

It will be observed that the runner members are disposed in different but parallel vertical planes; that any of said runners 115 can pass others which may be held against forward movement by the stop pins, and that the runner members are capable of being manipulated manually and moved independently as occasion may require,—thus 120 facilitating the easy and quick operation of the device.

To reproduce the movements of the ball over the field, I provide two members 38 and 39, one of which (38) is preferably a 125 hollow sphere of transparent material or translucent material, such as celluloid, representing the ball and located in front of the field, and the other (39) a controlling member located in rear of the board. The 130

ball 38, at the front, is secured to cords 40, which cords are wound at their ends on reels 41 located adjacent to the upper edge of the supporting frame 1 near the corners thereof. The ball controlling member 39 (which is provided with a handle 42) is connected to cords 43, the opposite ends of said cords being wound on reels 44. The reels 41 and 44 are secured to shafts 45 journalized in the supporting frame 1, the reels 41 being at the front, and the reels 44 being at the rear of the same. Fixed to the rear end of each reel 44 is a reel 46 carrying a cord 47 provided with a counter-weight 48. The cord 47 is wound on the reels in a direction opposite to that of the cords 43, so that as the ball member 39 rises or falls, the weight 48 will wind up or let out the cords 47, and as it moves sidewise the cords will wind up on the reels toward which the ball member is moving and unwind from the other, the weights 48 being just sufficient to maintain the cords under proper tension. Secured to the ball member 38 is a tension cord 49, which extends downwardly from said ball member and after passing about reels 50, 51 and 52, is provided at its depending end with a weight 53. A tension cord 53^a is also connected with ball controlling member 39 and after passing about reels 54, 55 and 56, its depending end has a weight 57 attached thereto.

The cords above described also form electrical conductors, and the cords 40, 40 are electrically connected with the terminals of an incandescent lamp 58 contained within the ball member 38 for illuminating the latter. One terminal of a battery 59 may be connected by a conductor 60 with the left hand shaft 45 (Fig. 10) while the other terminal of said battery is connected, by a conductor 61 with the reel 54. The handle 42 of the control ball member 39, carries a manually operable switch 62, one member of which is connected by a conductor 63 with the cord 53^a, while the other member of said switch is connected by a conductor 64 with the right hand cord 43. (Fig. 10). When the switch 62 is closed, the circuit may be traced as follows: from the battery 59, by conductor 60 to left hand reel 44, by shaft 45 to reel 46; by left hand cord 40 to the lamp 58 in the ball member 38; by right hand cord 40 to right hand reel 46; by shaft 45 to reel 44; then by right hand cord 43 and conductor 64 to one member of the switch 62; from the other member of said switch, by way of conductor 63 to cord 53^a, to reel 54, and then by conductor 61 to the battery 59. It will of course be understood that suitable insulation 63^a will be provided to electrically separate the shafts 45 from the frame 1 and for preventing the current from reaching parts of the

cords which form no part of the electrical circuit.

With the construction and arrangement of parts and circuits above described, the ball member may be illuminated at the will of the operator to facilitate the more ready understanding by the audience of the information to be imparted.

The outfield portion of the board may be made with an opening 65 and on the rear face of the board, a pocket 66 is located to receive a plurality of slides 67, each provided with a lug 68 for manipulating it. One of these slides may contain the word "Wild"; another, the word "Fly", another the word "Muff" and another indicating that a batter has been hit, or data giving other or additional information regarding the details of the plays may be indicated on these slides.

The board may also be provided with other pockets 69, 70, 71 and 72, labeled respectively "Out", "Runs", "Stks", and "Ball." These pockets carry slides 73 bearing figures, and are provided with lugs 74 for moving said slides outwardly from the inner ends of the pockets so that the figures thereon may be exhibited to be read in connection with the labeling on the pockets. The various slides will be operated from behind the board, and the labeling on their rear faces may be read through openings in the board as shown in Fig. 2, so that the operator may know what slide is being displayed. The board may also be provided on its rear face with the same labeling of the various positions as appears on the front of the board, for the guidance of the operator.

A panel 75 may be located under the field member and between the racks 3-3, said panel representing a box score.

Various changes might be made in the details of construction of my invention without departing from the spirit thereof or limiting its scope and hence I do not wish to restrict myself to the precise details herein set forth.

Having fully described my invention, what I claim as new and desire to secure by Letters-Patent, is:

1. A bulletin board comprising a member representing a field, a plurality of runner members movable independently of and past each other, operating means for said runner members, and means for limiting the movement of one or more of said runner members relatively to the others.

2. A bulletin board comprising a member representing a field, a plurality of runner members rotatable independently of each other for unlimited distances, operating means common to all of said runner members, and means for stopping the movement of one or more of said runner members.

- 4
3. A bulletin board comprising a member representing a field, a plurality of runner members movable unlimited distances independently of each other, centrally located friction devices coöperating with all of said runner members, means for moving said runner members, and means for stopping the movement of any of said runner members without interfering with the movement of the others. 10
4. A bulletin board comprising a member representing a field, a plurality of radial runner members having a common centrally located pivotal mounting and independently movable for unlimited distances, operating means common to all of said runner members, and means for stopping the movement of any of said radial runner members independently of the others. 15
5. A bulletin board, comprising a member representing a field, a plurality of radial runner members having a common pivotal mounting and movable independently of and past each other, common operating means for said radial runner members, and means for limiting the movement of any of said radial runner members without interfering with the movement of the others. 20
6. A bulletin board, comprising a member representing a field, a plurality of extensible runner members movable independently of and past each other, and adjustable stop means movable into the paths of runner members when the latter are extended. 30
7. A bulletin board comprising a member representing a field, a plurality of parallel runner members disposed in different planes, a centrally located shaft on which said runner members are pivotally mounted, disks interposed between said shaft and the runner members and between the runner members, means for applying yielding tension to said disks and runner members, means for turning said shaft to move the runner members, and means for stopping the movement of any of said runner members independently of the others. 40
8. A bulletin board comprising a member representing a field, a plurality of runner members movable independently for unlimited distances, a centrally located shaft on which said runner members are pivotally mounted, friction devices connecting the runner members with said centrally located shaft, means for operating said shaft, and adjustable stop devices for the runner members. 50
9. A bulletin board, comprising a member representing a field, a plurality of runner members movable independently for unlimited distances, a centrally located shaft on which said runner members are pivotally mounted, friction devices connecting the runner members with said shaft, means for regulating the tension of said friction de- 60
- vices, and adjustable stop devices for the runner members. 70
10. A bulletin board, comprising a member representing a field, a plurality of runner members movable independently for unlimited distances, a shaft on which said runner members are pivotally mounted, friction devices connecting said runner members and shaft, an operating shaft, gearing between said operating shaft and the shaft on which the runner members are mounted, and adjustable stop devices for said runner members. 75
11. A bulletin board comprising a member representing a field, said member having runway openings and openings representing base positions at the intersections of the runway openings, a plurality of radial runner members adaptable to project across said runway and base openings and movable behind and visible through the same, and means for obscuring the runner members at the base openings. 80
12. A bulletin board, comprising a member representing a field, said member having runway openings and openings representing bases at the intersections of the runway openings, a plurality of radial runner members adaptable to project across and movable behind said runway and base openings 85 so as to be visible through the same, and slides movable over the base openings for obscuring the runner members at the base positions. 90
13. A bulletin board, comprising a member representing a field having runway openings and base openings representing bases at the intersections of the runway openings, a plurality of radial independently movable runner members movable past the runway 95 and base openings, operating means common to all of said runner members, adjustable stops for arresting any of the runner members at and between the base openings, and adjustable means for obscuring the runner members at the base openings. 100
14. A bulletin board comprising a member representing a field and having runway openings and base openings at the intersections of the runway openings, a plurality of pivoted arms radiating from a common center and constituting runner members, each of said arms comprising relatively movable parts whereby said arms may be extended past the runway and base openings, means for arresting said arms, when extended, at and between base openings, and adjustable means for obscuring the extended runner member arms at the base openings. 115
15. The combination with a member representing a field, of a plurality of runner members movable in different planes and capable of passing each other. 120
16. The combination with a member representing a field, of a plurality of extensi- 125
- 130

ble runner members movable independently in different planes.

17. The combination with a member representing a field, of a plurality of runner members movable in different planes, a rotatable mounting for said runner members and friction devices interposed between said rotatable mounting and said runner members.
18. The combination with a member representing a field, of a plurality of runner members, a mounting for said runner members, friction devices interposed between said mounting and runner members, and an operating means common to all of said runner members, said operating means connected with said mounting for turning the same to transmit motion to each of the runner members through the medium of said friction devices.

19. The combination with a member representing a field, of a plurality of runner members, all portions of each of which are movable in a different plane from those of the others, said runner members being movable independently of each other.

20. The combination with a member representing a field, of a plurality of extensible runner members, and view obstructing means for concealing said runner members at the bases.

21. The combination with a member representing a baseball field, of a movable runner member and means including manually operable shields at the "bases" over the path of the runner member and manually operable stop devices adjacent to the "bases," whereby a runner play may be set before it is executed.

22. The combination with a member representing a baseball field having the diamond portion separated from the remainder of the field to form runway and base openings, of a plurality of runner members all movable in a plane behind the field mem-

ber and adapted to extend across and be movable behind said runway and base openings, said runner members being disposed in different planes and movable past each other.

50

23. The combination with a member representing a baseball field having its diamond portion spaced from the remainder of the field to provide runway and base openings, of radial runner members disposed behind the field member and movable past said openings, a plurality of adjustable stop pins movable into the paths of the runner members, and means for supporting the stop pins.

60

24. The combination with a member representing a baseball field having its diamond portion spaced from the remainder of the field to provide runway and base openings, of radial runner members disposed behind the field member and movable so as to be visible through said openings, a frame disposed behind and spaced from the field member, and adjustable stop pins mounted on said frame and movable into the paths of the runner members when the latter are moved behind the runway and base openings.

65

25. The combination with a member representing a baseball field and having openings representing runways and bases, of a plurality of radial runner members behind said field member and adapted to pass each other and be visible through said openings, and means for obscuring any of said runner members from view through said openings.

70

In testimony whereof I have signed this specification in the presence of two subscribing witnesses.

PAUL C. OSCANYAN.
